UNITED STATES PATENT OFFICE.

FREDERICKA L. BANNIHR, OF ATLANTIC CITY, NEW JERSEY.

DESIGN FOR A COMBINATION BRASSIÈRE-GIRDLE.

59,574.

Specification for Design.

Patented Nov. 8, 1921.

Application filed July 20, 1921. Serial No. 486,316. Term of patent 14 years.

To all whom it may concern:

Be it known that I, FREDERICKA L. BANNIHR, a citizen of the United States, residing at Atlantic City, in the county of Atlantic and State of New Jersey, have invented new, original, and ornamental Design for a Combination Brassière-Girdle, of which the following is a specification, reference being had to the accompanying drawing.

The combination-brassière-girdle is a step-in garment to be worn in place of a brassière and girdle.

Fig. 2 is a plan view of the back of the combination brassière-girdle.

I claim—

The ornamental design for a combination-brassière-girdle as shown.

FREDERICKA L. BANNIHR.
